Primary Examiner — Cathron C Brooks*Assistant Examiner* — Andrew T Nemeth(74) *Attorney, Agent, or Firm* — Veritay Group, IP; Susan Fentress(57) **CLAIM**

I claim the ornamental design for a display screen portion with graphical user interface, as shown and described.

DESCRIPTION

FIG. 1 is a front view of a display screen portion with graphical user interface showing a first embodiment of my new design; and,

FIG. 2 is a second embodiment thereof.

The outermost broken line rectangle in each figure illustrates a portion of a display screen. The broken line text in FIG. 1 illustrates portions of the graphical user interface. None of the broken lines form part of the claimed design.
